MAILING CARD AND ENVELOPE

John H. Coakley, Jr., Medford, Mass.

Application August 3, 1942, Serial No. 453,339

7 Claims. (Cl. 229—92.8)

This invention relates to an improved mailing device comprising a combined card and envelope. It is an object of the invention to provide a card and envelope mailer which is simple in structure and easy to assemble and use. It is a further object of the invention to provide a card having an envelope which is strongly made so as to minimize possible loss of contents.

For a more complete understanding of the invention and of the various advantages inherent therein, reference may be had to the following description of certain illustrative embodiments thereof, and to the drawing of which

Figure 1 is a plan view of a blank from which an embodiment of the invention may be made.

Figure 2 is a plan view of an auxiliary strip to be used with the blank shown in Figure 1.

Figure 3 is a fragmentary plan view of the blank and strip assembled.

Figure 4 is a fragmentary plan view of the finished article ready for use.

Figure 5 is a section on the line 5—5 of Figure 4.

Figure 6 is a section on the line 6—6 of Figure 4.

Figure 7 is a sectional view similar to Figure 6 but showing the envelope sealed.

Figure 8 is a perspective view of the device shown in the preceding figures combined with a foldable extension adapted to bear reading matter.

As shown in Figures 1 and 2, a device embodying the invention may be made from two pieces of material, a sheet 10 of suitable cardboard such as tag stock or the like and a strip 12 of paper which is preferably strong and tough but is considerably thinner than the cardboard used on the sheet 10. The blank shown in Figure 1 is substantially rectangular in shape and is provided with a projection 14 from its upper edge to serve as a closure flap as hereinafter described. The blank 10 includes an end portion 16 extending from an end of the blank as far as the projection 14, the length of this end portion being substantially equal to the width of the projection 14. Along two edges of the end portion 16 are narrow flange portions 18 and 20 which are integral with the blank 10. These flanges are preferably beveled at their mutually adjacent ends which are at the common corner 22, so that when they are bent back against the body of the end portion 16 as indicated in Figure 3, they will not overlap each other.

The strip 12 shown in Figure 2 is a lining member adapted to be built into a pocket or envelope as hereinafter described. The width of the strip 12 is substantially equal to the length of the end portion 16, the length of the strip 12 being somewhat longer than the width of the blank 10, so that when the strip 12 is superposed upon the

end portion 16 as indicated in Figure 3, the upper end portion 24 of the strip will project as a flap beyond the upper edge of the end portion 16 of the blank 10. When the strip 12 has been placed on the end portion 16 as described, the flanges 18 and 20 are folded back against the upper face of the strip and are cemented thereto by any suitable adhesive. Adhesive is thereupon applied to or activated on the exposed faces of the flanges 18 and 20, and may also be applied to or activated on a part or all of the strip 12 as shown in Figure 3, with the exception of the flap 24 of the strip which projects above the upper edge of the blank. The end portion 16 together with the strip 12 is thereupon folded toward the right on a line of fold aligned with the left-hand edge of the flap 14. The folded end portion and strip are then pressed firmly against the body of the blank 10 so as to form a pocket or envelope as indicated in Figures 4, 5 and 6. This envelope is then ready to receive coins, tickets, or similar objects 28 between the folded-over end portion 16 of the blank which serves as the front wall of the pocket, and the liner member 12 which is backed by the body of the blank 10. As indicated in Figures 6 and 7, the lower edge of the liner 12 is disposed between the front wall of the pocket and the flange 20. This arrangement prevents the escape of any of the contents of the envelope through the bottom thereof if the flange 20 should happen to separate partially from the body of the blank 10 to which it is cemented. For convenience, the front faces of the flaps 14 and 24 are preferably gummed, so that when it is desired to seal the envelope, these flaps may be moistened and folded down against the front face of the envelope. This provides a reinforced closure for the top of the envelope which affords added security for the contents thereof.

A mailing device such as herein described is useful for mail order houses and the like in soliciting orders where such orders may in some cases be accompanied by a check or cash. It may be desirable to employ considerable advertising matter in connection with the order blank. For this purpose, a combination of the mailing device with an extended form 30 may be employed as indicated in Figure 8. This may consist of a sheet of suitable cardboard such as tag stock having, for example, a width equal to the length of an ordinary postal card and a length equal to some multiple of the width of such a card, the specimen illustrated in Figure 8 having a length three times the width of the ordinary postal card. The sheet 30 comprises a number of sections or panels defined by lines of fold 32 and 34 so that the folded sheet can be readily inserted into an ordinary business envelope. The lowermost section or panel is originally provided

with an end extension like the end portion 16 projecting beyond the side edge of the sheet 30. This end projection is folded with a liner element into the form of a pocket such as has been hereinbefore described. In order to provide a suitable closure flap 36 to be used with the closure flap 24 of the liner element, the lower panel of the sheet 30 is defined by a line of weakness formed by scoring, perforating or otherwise weakening the stock along the fold line 34 as far as the envelope and then along an offset line 38 which extends perpendicular to the line 34 and then parallel thereto so as to define the flap 36. When the lower panel of the sheet 30 is detached from the remainder of the strip along this line of weakness, it then becomes substantially identical with the mailer illustrated in Figure 4.

It is evident that various modifications and changes may be made in the embodiments of the invention herein illustrated and described without departing from the spirit or scope thereof as defined in the following claims.

I claim:

1. A combined card and envelope mailer comprising a card of tag stock or the like having an end portion folded over against the adjacent portion of the body of the card, said end portion having integral flange elements along two of its edges folded in between it and the body of the card and cemented to said body to form a pocket, and a liner piece fitted into said pocket, one face of said liner piece being cemented to said flanges, said card and liner piece having portions forming closure flaps foldable over the mouth of said pocket against the outer face of said folded end portion of the card.

2. A combined card and envelope mailer comprising a card having a plurality of body sections of approximately postal card size foldable upon one another to form a multi-layer mailing card, one of said sections having an integral end-extension folded back against its face, said end-extension having integral flanges along two of its edges folded in between said extension and the adjacent portion of said body section and cemented to the face of said body section so that a pocket is formed between said extension and said adjacent portion of the body section, a liner piece fitted into said pocket and cemented to said flanges and to said face of the body section, said liner piece having a free flap extending between the mouth of said pocket and foldable down against the outer face of said extension to close the pocket, and a line of weakness between said one section of the card and the next adjoining section to facilitate separation of said sections, said line of weakness extending along the line of fold between said sections except at said pocket, the remainder of said line of weakness being arranged to define a closure flap foldable down to cover and reinforce the flap on the liner piece.

3. A combined card and envelope mailer comprising an elongated card of tag stock or the like having an end portion folded over against the adjacent portion of the body of the card, said end portion having an integral flange portion along its lower edge folded up and cemented to the body of the card, and a liner piece interposed between said end portion and the body of the

card, said liner piece having its lower margin disposed between said flange and the face of said end portion and cemented to said flange, the side edge of said end portion and the adjacent side edge of the liner piece being cemented together to the face of the card to form a pocket, and said card and liner piece having closure flaps foldable over the mouth of said pocket against the outer face of said folded end portion of the card.

4. A combined card and envelope mailer comprising a sheet of suitably stiff paper material having an end portion folded over against the adjacent body of the card, said end portion having integral flange elements along two of its free edges folded in between itself and the body of the card and adhesively secured to the body to form a pocket open at one end, and the card having a flap element contiguous to the open end of the pocket adapted to be folded thereover against the outer face of said folded-over end portion of the card; said card and envelope combination being also combined with a panel connected detachably to the outer end and one side of said flap and to the adjacent edge of the card 20 and being foldable with said flap element along the line of said edge of the card over and against the face of the card and envelope.

5. A combined card and envelope mailer comprising a sheet of suitably stiff paper material having an end portion folded over against the adjacent body of the card, and a liner piece located between said folded-over portion and the body of the card; said liner piece and folded-over portion being secured together and to the card 30 at their bottom margins and at the originally free side margin of the folded-over portion to form a pocket open at one end, and the liner having an extension protruding from the pocket and providing a closure flap adapted to be folded over the mouth of the pocket against the outer face of said folded-over end portion.

6. A combined mailing card and envelope comprising a sheet of suitably stiff paper material having a main body portion and an end portion 40 united on a folding line, the end portion having inturned flanges on two of its free edges and being folded on said folding line against the body portion with said flanges interposed and adhesively united to the body portion, one free edge of the end portion being unconnected with the body portion, whereby a pocket open at one end is formed by said portions, and the card having a flap element contiguous to the open end of said pocket adapted to be folded thereover against the outer face of said folded-over end portion.

7. A combined card and mailing envelope comprising a sheet of suitably stiff paper material having a body portion and an end portion united on a folding line, said end portion being folded on 50 said line against the body portion and being secured to the latter along the margins of its bottom and its originally free side edge by adhesive between said margins and the adjacent surface areas of the body portion, its upper edge and the area within said margins being free from connection with the body portion, whereby a pocket open at one end is provided; the card having also a flap element contiguous to the open end of the pocket adapted to be folded thereover against the outer face of said end portion.
